(57) CLAIM

The ornamental design for a cleaning tool, as shown and described.

DESCRIPTION

FIG. 1 is a perspective view of a cleaning tool according to our new design;

FIG. 2 is a front side view of the cleaning tool of FIG. 1;
FIG. 3 is a rear side view of the cleaning tool of FIG. 1;
FIG. 4 is a left end view of the cleaning tool of FIG. 1;
FIG. 5 is a right end view of the cleaning tool of FIG. 1;
FIG. 6 is a top view of the cleaning tool of FIG. 1; and,
FIG. 7 is a bottom view of the cleaning tool of FIG. 1.
The broken lines in the drawings depict portions of the cleaning tool that form no part of the claimed design.
